UNITED STATES PATENT OFFICE.

EMIL PIRO, OF NEW YORK, AND VIRGINIUS Z. CARACRISTI, OF BRONXVILLE, NEW YORK, ASSIGNORS TO PIRO COAL DISTILLATION SYSTEMS, INC., OF NEW YORK, N. Y., A CORPORATION OF DELAWARE.

APPARATUS FOR DISTILLATION.

Application filed April 4, 1922. Serial No. 549,394.

Our present invention relates to apparatus for distillation in which the material to be distilled is subjected to heat in a distillation chamber to drive off the gases therefrom, and will be best understood from the following description and the appended drawings, in which Figure 1 is a vertical section of one form of our invention; Fig. 2 is a section of Fig. 1 on the line 2—2, looking in the direction of the arrows, and Fig. 3 is a vertical section of a modification.

Like reference characters indicate like parts in the several views.

In the illustrative arrangement shown in Figs. 1 and 2, the distillation chamber 10 is provided with a receptacle containing a bath 11 of any suitable molten material. We have found the metal lead suitable for our purpose, but it will be understood that any other easily fusible material may be used, if it does not volatilize at the distillation temperature and conducts heat readily. At one end of the chamber is provided a hopper 12 by which the material to be distilled, such as coal or the like, may be fed, preferably in a relatively thin layer, to the surface of the bath 11. At the opposite end of the chamber 10 is a discharge chute 13 and in the roof of the chamber is a gas outlet 14. The side walls 15, 16 of the chamber 10 are carried down below the surface of the bath 11, the bath receptacle extending outside of these side walls, as shown best in Fig. 2. Adjacent these side walls is a plurality of chambers, the chambers 17 being combustion chambers and the chambers 18 exhaust chambers.

Extending through the bath is a plurality of tubes 19 which have upturned ends entering respectively the chambers 17 and 18. The side walls 15, 16 are provided with openings through which the tubes 19 pass, these side walls being continued down between the tubes to hold them in position. The upturned ends project above the surface of the bath 11. The inlets 20 connected to burners supplying a combustible mixture of air and gas (not shown) lead into the combustion chambers 17 and the chambers 18 are connected through

the gas exits 21 with a stack or other suitable means to dispose of burnt gases.

In the form illustrated in Figs. 1 and 2, a means to forward the material received from the chute 12 is provided in the form of a number of chains 22 which pass over suitable pulleys on the shafts 23 and 24 at opposite ends of the distillation chamber. Idlers 25 may be conveniently provided to support the chain at the right-hand end of Fig. 1. The shaft 23, and therefore the chains 22, is given a step-by-step motion through an eccentric 26 on a shaft 27 and a connecting rod 28 actuating a ratchet 29, the shaft 27 being turned from any suitable source of power. The rotation of the shaft 23 will move the chains 22 so as to carry the lower run thereof to the right of Fig. 1. The shaft 23 may also be provided with toothed portions to feed the material from the hopper 12 to the surface of the bath.

When the apparatus just described is used for the distillation of coal, combustible gases are passed from the inlets 20 into the combustion chambers 17 where they are ignited and from whence they pass through the heating tubes 19, the burnt gases therefrom passing out through the gas outlets 21. The heat from these burnt gases is transmitted through the walls of the tubes 19 directly to the material of the bath 11 to maintain it in a molten condition, and to supply heat to the material to be distilled. The coal passes from the hopper 12 by the rotation of the shaft 23 and is spread over the surface of the bath in a relatively thin layer, and, by engagement with the links of the chains 22, the coal is carried along the surface of the bath on which the coal will float, receiving heat directly from the material of the bath. The gases driven off from the coal pass out of the gas outlet 14 and by the time the coal reaches the right-hand end of the chamber 10, it is reduced to coke which passes up over the plates 10' and into the chute 13. If desired, devices may be supplied at the right-hand end of the chains 22 which will remove the coke which may adhere to the chains.

If lead be used for the bath and the chains are made of iron or steel, the run of the chain adjacent the bath will float on the surface thereof so as to extend up into the mass of coal, and, by reason of the plasticity of the coal as it is being coked, the coal will be engaged by the chains and moved therewith. Instead of moving the shaft 23 intermittently, it may be turned continuously and obviously many other forms of feeding devices 10 may be used instead of that illustrated.

By heating the bath internally, as by the tubes 19, the heat for the distillation will not be obliged to pass through the refractory material forming the receptacle for the bath, so that the life of the refractory material will be prolonged. Moreover, the heat will be supplied very close to the point at which it is used in the distillation, so that losses will 15 be decreased. Because the receptacle for the bath is comparatively cool, any cracks which may be formed therein will be sealed by the molten material which will enter these cracks and be cooled as it passes away from the bath. 20 By arranging the tubes in the manner described, it will be obvious that no means for attaching them in position is required, and that there is no possibility of leaks of the gas used in the heating, the liquid of the bath 25 forming a seal around the tubes.

In Fig. 3, we have shown a modification in which the material to be distilled is forwarded along the surface of the bath by a chain made up of plates 30 which form a continuous support or platform for the material, the material being fed from the hopper 12 to this continuous platform. If the material of the bath be lead, for instance, the plates of the chain will float thereon, so that the coal does not contact directly with the 30 lead. The chain passes around sprockets on the shafts 31, 32, the sprocket 31 being actuated by any suitable mechanism either continuously or intermittently, as, for example, by mechanism indicated in Fig. 1 for driving shaft 23. In the form illustrated, the chain, instead of returning through the distillation chamber, passes around and beneath the receptacle for the bath. When this form is 35 used, it is preferable to arrange the lower run of the chain so that it travels in a closed space to preserve the heat in the plates of the chain and the lower run may be sufficiently removed from the bottom of the bath receptacle to prevent the heating of the exterior of the receptacle.

As will be obvious, the chains shown in Fig. 1 may also be arranged to pass beneath the receptacle for the bath on the return run.

In the distillation of certain materials, such as some grades of coal, the coal becomes sufficiently plastic to adhere to the walls of the distillation chamber if the coal contacts therewith. Such contact would be prevented 40 by distributing the coal on the center of the

bath only, but to insure that it will not spread out and be brought into contact with the side walls 15, 16, we may provide at the sides of the hopper 12 in either one of the illustrated embodiments of the invention, supplemental 70 hoppers 33, 34, through which will be fed a material which will not be sticky at the temperature of the bath, such, for instance, as coke. When these supplemental hoppers are used, a layer of such material will be 75 supplied to either side of the bath between the side walls 15, 16 and the layer of material being distilled, and this additional material will be carried through the bath in the same manner as the material being distilled to form 80 a protective zone, as it were, to prevent the material being distilled from coming into contact with the side walls. If the material being distilled is coal and the additional material is coke, then the entire mass may be 85 delivered into the common chute 13. If a material is used which is to be kept separate from the products produced by the distillation, then the chute 13 would be divided so as to provide separate parts, each to receive one 90 kind of material.

While we have shown illustrative forms of our invention, it will be understood that the embodiment of the same may be widely varied.

We claim:—

1. A distillation apparatus for solid materials comprising a distillation chamber, a bath of molten material in said chamber, means to feed the material to be distilled to 100 a point adjacent the surface of the bath at one end thereof, means to forward the material above and adjacent the surface of the bath, and heating means for the bath located in the molten material, said heating means 105 comprising a tube with upturned ends, the main body of the tube extending through the bath and crosswise of the direction of travel of said forwarding means and beneath the surface thereof and the upturned ends projecting above the surface of the bath.

2. A distillation apparatus for solid materials comprising a distillation chamber, a bath of molten material in said chamber, means to feed the material to be distilled to 115 a point adjacent the surface of the bath at one end thereof, means to forward the material above and adjacent the surface of the bath, heating means for the bath located in the molten material, said distillation chamber having side walls extending below the surface of the bath and said heating means comprising a tube with upturned ends, with the main body of the tube extending through the bath and beneath the said side walls and 125 the upturned ends projecting above the surface of the bath outside the distillation chamber, and means for supplying combustible gases to one of said upturned ends.

3. A distillation apparatus for solid ma- 130

terials comprising a distillation chamber, a bath of molten material in said chamber, means to feed the material to be distilled to a point adjacent the surface of the bath at one end thereof, and an endless flexible forwarding device having a specific gravity less than that of the material of the bath and having a portion of its run arranged to float on the bath, to forward the material to be distilled 10 parallel to the surface of the bath.

4. A distillation apparatus for solid materials comprising a distillation chamber, a bath of molten material in said chamber, means to feed the material to be distilled to 15 a point adjacent the surface of the bath at one end thereof, and an endless, flexible, moving platform of jointed plates having a specific gravity less than that of the material of the bath and adapted to transmit the heat of 20 the bath to the material to be distilled, said platform having a portion of its run arranged to float on the bath and to forward the material to be distilled parallel to the surface of the bath.

25 5. A distillation apparatus for solid materials comprising a distillation chamber, a bath of molten material in said chamber, an endless, flexible, moving platform of jointed heat-transmitting plates having a specific 30 gravity less than that of the material of the bath and having a portion of its run floating on the surface of the bath with the tops of the plates above and adjacent to the surface of the bath, and means to feed the material 35 to be distilled to the top of the plates at one end of the bath, whereby such materials are supported out of contact with the material of the bath and carried parallel to the surface thereof while being distilled.

40 6. A distillation apparatus having a bath of molten material, and heating means for the bath located within the bath, said heating means comprising a combustion chamber, an exhaust chamber and a tube with upturned 45 ends extending beneath the surface of the bath and having its ends extending loosely into said combustion and exhaust chambers.

50 7. A distillation apparatus having a bath of molten material, heating means for the bath located within the bath, said heating means comprising a combustion chamber and a tube with upturned ends, the main portion 55 of the tube being located beneath the surface of the bath and substantially parallel with the same and the ends extending above said surface, and means for supplying combustible gases through the combustion chamber to one of the upturned ends, said end of the tube extending loosely into said combustion chamber.

60 8. A distillation apparatus comprising a bath of molten material, a distillation chamber having walls extending below the surface of the bath and removed from the edges 65 thereof, heating means for the bath, comprising

ing a tube having upturned ends, with the main portion of the tube extending through the bath and beneath said walls and with the upturned ends outside the distillation chamber and above the surface of the bath, and 70 means for supplying combustible gases to one of the upturned ends.

9. A distillation apparatus comprising a bath of molten material, a distillation chamber having walls extending below the surface 75 of the bath and removed from the edges thereof, a combustion chamber and an exhaust chamber at opposite sides of the distillation chamber and outside the walls thereof, a tube having upturned ends, with the main 80 portion of the tube extending through the bath and beneath said walls and with the upturned ends extending above the surface of the bath, one of said ends communicating with the combustion chamber and the other 85 with the exhaust chamber, and means for supplying combustible gases to the heating chamber.

10. A distillation apparatus for solid materials, comprising a distillation chamber, a 90 bath of molten material in said chamber, means to feed the material to be distilled to a point adjacent the surface of the bath at one end thereof, means to forward the material above and adjacent the surface of the 95 bath, and means to maintain between the side walls of the chamber and the material to be distilled, a quantity of other material which is non-adherent to the side walls at the temperature of the bath.

11. A distillation apparatus for solid materials comprising a distillation chamber, a bath of molten material in said chamber, means to feed a layer of the material to be distilled to a point adjacent the surface of the 105 bath at one end thereof and out of contact with the side walls of the chamber, means to feed a layer of other material to a point adjacent the surface of the bath and between the side walls and the layer of material to 110 be distilled, and means to forward both materials above and adjacent the surface of the bath, said other material being non-adhering to the side walls at the temperature of the bath.

115 12. A distillation apparatus for solid materials comprising a distillation chamber, a bath of molten material in said chamber, means to feed the material to be distilled to a point adjacent the surface of the bath at one end thereof, an endless flexible forwarding device having one portion of its run located above and adjacent the surface of the bath and adapted to forward the materials to be distilled parallel to the surface of the 120 bath and having its return run beneath the bath, and means to heat the bath, comprising tubes extending beneath the surface thereof at right-angles to the line of travel of the conveyor.

13. A distillation apparatus for solid materials comprising a distillation chamber, a bath of molten material in said chamber, means to feed the material to be distilled to a point adjacent the surface of the bath at one end thereof, and an endless flexible forwarding device having one portion of its run located above and adjacent the surface of

the bath and adapted to forward the materials to be distilled parallel to the surface ¹⁰ of the bath, rotary supports for said conveyor at either end of the bath, and means pulling on the non-material-forwarding run of the conveyor to move said conveyor.
